UNITED STATES PATENT OFFICE.

THOMAS F. KRAJEWSKI, OF PATERSON, NEW JERSEY.

WHEELED VEHICLE.

SPECIFICATION forming part of Letters Patent No. 289,421, dated December 4, 1883.

Application filed June 18, 1883. (No model.)

To all whom it may concern:

Be it known that I, THOMAS F. KRAJEWSKI, of Paterson, in the county of Passaic and State of New Jersey, have invented a certain new and 5 useful Improvement in Wheeled Vehicles, of which the following is a specification.

My improvement relates particularly to vehicles which are adapted for traveling upon the ground or along rails.

10 In the accompanying drawings, Figure 1 is a plan of a vehicle embodying my improvement. Fig. 2 is a longitudinal section thereof. Fig. 3 is an end view thereof, and Fig. 4 is a transverse section of the same.

15 Similar letters of reference designate corresponding parts in all the figures.

The frame A A' A² A³ of the body or platform of the vehicle is made, as here shown, of beams or girders A, which are I-shaped in the 20 cross-section, and may be constructed of iron or other suitable material. These beams or girders are connected at the ends by angle-pieces and bolts or other suitable means. Beams or girders A² extend lengthwise of the 25 frame, and may be channel or trough shaped in the cross-section. Beams or girders A³ extend between the beams or girders A². Between the beams or girders A' and the beams or girders A, which are parallel therewith, extend 30 beams or girders A³. This frame A A' A² A³ may be covered with planks or other material.

B designates the wheels of the vehicle, and C designates the axles of the wheels. The wheels B have wide treads a, circumferential 35 grooves b, and flanges c. The grooves b are sufficiently wide to fit upon ordinary railroad-rails D, the treads a are located at the outer sides of the grooves, and the flanges c are arranged at the inner sides of the grooves.

40 Owing to this relative arrangement of the grooves, treads, and flanges, a greater space is provided between opposite wheels than would otherwise exist. The increase of this space is advantageous because it enables the wheels 45 the better to clear stumps, projecting stones, or irregularities in the surface of the ground between the rails. Moreover, the arrangement of the treads at the farthest possible distances apart is advantageous when the vehicle is removed from the rails and run over rough ground, for the body or platform of the

vehicle is then afforded a running base of greater lateral extension, which of course makes it more stable. The hubs of the wheels may be provided with lubricating chambers d, if 55 desirable. It will be observed that the treads a of the wheels B are approximately straight from side to side, and are destitute of flanges; hence they are well adapted for running over the ground and for turning curves. The 60 flanges c have no greater circumferential extension than the treads, and hence will not sink into the ground farther than the treads.

The axles C may be made of wrought-iron or other suitable material. They are provided with shoulders e near the ends, or, in other words, just in rear of the journals f. On the journals f, between the shoulders e and the wheels B, are collars g, and outside the wheels B other collars, h, are placed on the 70 journals. Linchpins i, passed through the journals outside the wheels and the collars h, secure the wheels in place on the journals. The axles just inward of the journals f are bent upward, and the central portion extends parallel with the journals, but is elevated considerably above the same. The elevated central portions of the axles are pivoted by center pins or king-bolts, E, to the beams or girders A² of the frame A A' A² A³; hence the 80 pairs of wheels may be adjusted at different angles relatively to the frame A A' A² A³ for the purpose of facilitating the turning of the vehicle. As shown, these pins or bolts E are provided with clips j, embracing the axles, and 85 secured thereto by bolts or rivets, and extend through the beams or girders A², and are secured thereto by nuts n. The elevation of the central portions of the axles is advantageous, because it enables them to clear stumps, stones, 90 and other projections from the ground, and also because it enables the axles to be connected directly to the frame of the body or platform of the vehicle. The wheels of the peculiar construction here shown, and the 95 axles having the elevated central portions, both conduce to allow ample clearance below the axles, the wheels having the outside treads giving a wide clearance laterally, and the axles with their elevated portions allowing 100 clearance in a vertical direction.

A forked draw-bar, G G', is connected to

each of the axles C. Each draw-bar has two diverging arms, G, which are provided with clips *k*, that embrace an axle and are bolted or riveted thereto, and an arm, G', that extends 5 in an opposite direction beyond the frame A A' A² A³. The arm G' is bifurcated at the outer end and provided with holes *l*, into which a coupling-pin, *p*, may be inserted. Under 10 each of these arms G' extends a guide-rod, *o*, which supports the arm, and yet allows it to move laterally. The ends of the rods *o* are fastened to the transverse beams or girders A of the frame A A' A² A³. The arms G of the 15 forked draw-bars extend beyond the axles C, and at the ends are connected by rods H. These rods are arranged in different planes, and cross each other so as to extend between obliquely-opposite arms. At the ends the 20 rods are bifurcated, so that they will embrace the ends of the arms G of the draw-bars, and they are connected to these arms of the draw-bars by pins *m*. When either draw-bar is moved laterally to swing around the pair of wheels and axle to which it is connected, the 25 rods H cause the other pair of wheels and axle to also swing around, so as to facilitate the movement of the vehicle around a curve. On the upper side of the arms G of the draw-bars are projections *q*, and on the lower side of the 30 beams or girders A² are stops *r*. Whenever the pairs of wheels and their axles are swung around sufficiently in moving the vehicle around a curve, some of the projections *q* on the draw-bar come in contact with the projections *r* on the beams or girders A², the wheels 35 and axles are precluded from swinging around any farther. The upper sides of the arms G of the draw-bars form bearings on which the projections or stops *r* on the car-frame move, and therefore form side bearings for supporting 40 the frame. These bearings do not prevent the frame from being readily lifted off the axle when the king-bolt or center pin, E, is removed. The stop projections *r* may be considered 45 as a part of the frame.

What I claim as my invention, and desire to secure by Letters Patent, is—

1. In a wheeled vehicle adapted for traveling over the ground or along rails, the com-

bination, with an axle, of two wheels mounted 50 thereon, severally having at the outer edge a wide tread suitable for running over the ground, the said tread being approximately straight from side to side and destitute of a flange, a groove located at the inner edge of 55 the tread suitable for fitting a rail, and a flange forming the inner side of the groove and extending circumferentially no farther than the tread, the said wheels being so arranged relatively to each other that their flanges and 60 grooves will be inward of their broad treads, substantially as specified.

2. In a vehicle designed for traveling over the ground or along rails, the combination of 65 an axle having a central elevated portion, and a pair of wheels having at the outer edges wide treads, which are approximately straight from side to side and destitute of flanges, and which are suitable for running over the ground, having 70 grooves at their inner edges, and having flanges forming the sides of the grooves opposite the treads and extending no farther circumferentially than the treads, substantially as specified, whereby an increased clearance 75 is afforded beneath the axle both in a vertical and lateral direction.

3. In a vehicle, a frame for a body or platform, an axle having its central portion elevated, a center pin or king-bolt connecting the central elevated portion of the axle to the 80 frame, and side bearings on the elevated portion of the axle on which said frame rests, all being so combined and organized that provision is afforded for raising said frame off the axle when the said pin or bolt is removed, 85 substantially as described.

4. In a vehicle, the combination of a platform or body, an axle, a forked draw-bar connected thereto, projections extending upwardly from the draw-bar, and projections extending downwardly from the platform or body, 90 substantially as specified.

THOMAS F. KRAJEWSKI.
